UNITED STATES PATENT OFFICE.

HENRY W. POWERS, OF PITTSFIELD, MASSACHUSETTS, ASSIGNOR TO
HENRY C. CLARK, JOHN W. CLARK, MOSES P. LAWTON, AND WAR-
NER G. MORTON.

DEVICE FOR TILTING WAGON-BEDS.

SPECIFICATION forming part of Letters Patent No. 245,745, dated August 16, 1881.

Application filed May 11, 1881. (Model.)

To all whom it may concern:

Be it known that I, HENRY W. POWERS, of Pittsfield, in the county of Berkshire and State of Massachusetts, have invented certain new and useful Improvements in Devices for Tilting Wagon-Beds; and I do hereby declare that the following is a full, clear, and exact description of the invention, which will enable others skilled in the art to which it appertains to make and use the same, reference being had to the accompanying drawings, which form a part of this specification.

Figure 1 is a perspective view, Fig. 2 is a vertical sectional view, Fig. 3 is a side view, and Fig. 4 is a longitudinal sectional view, of the device in position for operation.

Corresponding parts in the several figures are denoted by like letters of reference.

This invention relates to an improved device to be attached to wagons for the purpose of raising or tilting the wagon-bed so as to unload the same when required, thus converting an ordinary wagon into what is generally known as a "dumping-wagon;" and it consists in certain improvements in the construction of the same, which will be hereinafter fully described, and particularly pointed out in the claim.

In the drawings hereto annexed, A represents a hollow upright or standard provided upon its rear side with a vertical slot, B.

C is a rack-bar, sliding vertically in the upright A, and provided on one side with a lug, D, projecting through and sliding in the slot B, and having a pivoted shoe, E, bolted or otherwise suitably secured to the bed of the wagon, to which the device is attached.

The side of upright A is provided with laterally-projecting brackets F, having bearings G for a shaft, H, carrying a pinion, I, engaging the rack-bar C, and a ratchet-wheel, J, engaging a spring-pawl, K, pivoted upon the side of a crank-arm, L, journaled upon said shaft, and a gravity pawl or dog, M, pivoted to the side of upright A.

The upright A is pivoted at its lower end to a shoe, N, which is in practice bolted or oth-

erwise secured to the front end of the reach of the wagon, to which the device is applied. The shoe N and the front end of the reach are provided with vertical slots S T, to accommodate the lower end of the rack C. By this construction the upright or standard A may be made considerably shorter than would otherwise be possible, thus effecting a considerable saving in material, and consequently in cost of manufacture, as well as in space.

The operation of my invention will be readily understood from the foregoing description and by reference to the drawings hereto annexed.

The upright A is secured by the pivoted shoe N to the reach of a wagon, and the vertically-sliding rack-bar C by the pivoted shoe E to the front end of the wagon-bed. By working the crank L the shaft H and pinion I are rotated, thus raising the rack-bar and tilting the wagon-bed, which may be held at any desired inclination or angle by the pawl or dog M engaging the ratchet-wheel. The device is simple, easily operated, and may be readily attached to any ordinarily-constructed wagon.

I am aware that rack-and-pinion and screw-threaded devices have been before used for similar purposes, and such constructions are not sought to be covered broadly in this application.

I attach importance to the pivotal connection with the wagon-body.

What I claim is—

The vertically-recessed standard A, pivoted to the shoe N, and vertically-sliding rack C, pivoted to the body by means of shoe E, the shaft H, pinion I, ratchet J, crank L, and pawls K M, all constructed, arranged, and combined to operate as set forth.

In testimony that I claim the foregoing as my own I have hereto affixed my signature in presence of two witnesses.

HENRY W. POWERS.

Witnesses:

J. H. FRANCIS,
E. W. BUELL.
